UNITED STATES PATENT OFFICE

149,631

DESIGN FOR AN ELECTRIC WALL LAMP FIXTURE

Gordon F. Gluff, Chicago, Ill.

Application May 9, 1946, Serial No. 129,493

Term of patent 7 years

(Cl. D48—4)

To all whom it may concern:

Be it known that I, Gordon F. Gluff, a citizen of the United States, residing at Chicago, in the county of Cook and State of Illinois, have invented a new, original, and ornamental Design for an Electric Wall Lamp Fixture, of which the following is a specification, reference being had to the accompanying drawing, forming a part thereof.

Figure 1 is a front elevational view of an electric wall lamp fixture embodying my new design.

Fig. 2 is a side elevational view of the same.

Fig. 3 is a vertical sectional view taken approximately in the plane of line 3—3 of Fig. 2.

Fig. 4 is a sectional view taken in the plane of line 4—4 of Fig. 2 but on an enlarged scale.

The dominant features of the design reside in the portion shown in full lines in the drawing.

I claim:

The ornamental design for an electric wall lamp fixture, substantially as shown and described.

GORDON F. GLUFF.
